CLAIM

The ornamental design for a lift truck instrument panel, substantially as shown and described.

DESCRIPTION

FIG. 1 is a top plan view of a lift truck instrument panel embodying our new design;

FIG. 2 is a front end elevational view thereof;

FIG. 3 is a back end elevational view thereof;

FIG. 4 is a left side elevational view thereof; and

FIG. 5 is a right side elevational view thereof.

The bottom of the instrument panel is substantially flat and unornamented.
